SUPersonic SPACE CRAFT, OR THE LIKE

Mike Tecton, 5101 45th St. NW,
Washington, D.C. 20016

Filed Oct. 24, 1965, Ser. No. 87,921

Term of patent 14 years

(Cl. D71—1)

FIG. 1

FIG. 2

FIG. 3

FIG. 4

FIG. 1 is a top perspective view of a supersonic space craft, or the like, showing my new design;

FIG. 2 is an enlarged front elevational view thereof;

FIG. 3 is a bottom perspective view thereof;

FIG. 4 is a right elevational view thereof.

The side opposite that shown in FIG. 4 is a mirror image of the side shown.

The characteristic feature of my design resides in the flat configuration of the fuselage as best shown in FIG. 4.

I claim:

The ornamental design for a supersonic space craft, or the like, substantially as shown and described.
